F. J. Ryan,

By
Geo. P. Kimmel. Attorney

UNITED STATES PATENT OFFICE.

FREDERICK J. RYAN, OF TORONTO, ONTARIO, CANADA.

AUTO SIGNAL.

Application filed March 18, 1921. Serial No. 453,241.

To all whom it may concern:

Be it known that I, FREDERICK J. RYAN, a subject of the King of Great Britain, residing at Toronto, in the Province of Ontario and Dominion of Canada, have invented certain new and useful Improvements in an Auto Signal, of which the following is a specification.

This invention relates to automobile signals and more particularly to brake actuated devices of this character.

The object of the invention is to provide a simple and efficient signal of this character which is automatically displayed by the application of the brakes, and withdrawn on the release thereof.

Another object is to provide improved means for limiting the movement of the signal arm or semaphore member in both raised and lowered positions.

With these and other objects in view the invention consists of such novel features of construction as herein after shown and described, and then specifically pointed out in the claims, and in the drawings illustrative of the preferred embodiment of the invention.

In the accompanying drawings:—

Figure 1 represents a side elevation of a portion of an automobile in dotted lines with this improved signal shown applied.

Fig. 2 is a side elevation of the signal and its controlling mechanism shown partly in section and with parts broken out; and

Fig. 3 is a vertical sectional view through the signalling mechanism taken in a plane at right angle to that shown in Fig. 2.

In the embodiment illustrated the apparatus constituting this invention comprises an attaching block or casting 1 designed to be screwed or otherwise fastened to the bottom of the car body as shown clearly in Fig. 1 and to which is pivotally connected at one end a bar 2 mounted to oscillate longitudinally of the car which is provided with a plurality of longitudinally spaced apertures 3 for the connection of a substantially U-shaped stirrup member 4, the ends of which straddle the lower end of the bar 2 and are pivotally engaged with one of the apertures 3 a plurality of which are provided to adapt the apparatus for attachment to various makes of cars.

The crossbar 5 of the member 4 is apertured to receive a bolt 6 which is shown in Fig. 2 with the head thereof adjacent the inner face of said bar 5. An adjusting member 7 is connected with the threaded end of the bolt here shown in the form of a bar having its ends extended laterally at right angles as shown at 8, the bolt 6 extending through one of them and being secured by a nut, while engaged with the other end is a cable 10 having a knot 9 on its inner end to prevent it slipping through the aperture in the end 8 of the bar 7 with which it is connected. The cable 10 is preferably constructed of twisted steel wire to adapt it to withstand the strain to which it will be subjected and it is connected at its other end with one end of a coiled spring 11 mounted within a casing 12 attached to any suitable part of the car preferably at the rear thereof as is shown clearly in Fig. 1. This cable within the casing passes around pulleys 13 and 14 one of which is arranged at the upper end of said casing and the other at the lower end thereof, as is shown clearly in Figs. 2 and 3, the pulley 14 opening through the bottom of the casing so that the cable 10 may pass around the grooved periphery thereof and be guided in its longitudinal movements for a purpose presently to be described.

The casing 12 is provided at its lower end with a detachable cap-like closure 15 which is secured to the casing by the pintle 16 of which the pulley 14 is mounted as is shown clearly in Figs. 2 and 3. This closure 15 has a laterally extended apertured arm in the form of a plate 17 which is designed for attaching the casing to a supporting structure which may be any part of the car body or frame.

The upper pulley 13 as shown has a hub 18 fixedly mounted to its pintle or shaft 19 by a screw or otherwise (see Fig. 2.), said sleeve 18 operating as a spacer bearing against the opposed inner faces of the casing 12 to prevent longitudinal movement of the pintle.

A shaft 20 is rotatably mounted in the casing 12 above the pulley 13 and has fixedly mounted thereon the hub 21 of a head 22 of a signal arm or semaphore 23 which arm is mounted outside the casing and adapted to swing into position at right angles to the

casing when the signal is to be displayed and dropped down parallel with the casing when not in use. This arm 23 may have any desired indicia carried thereby such as the word "Stop" to indicate when it is swung into operative position that the vehicle upon which it is mounted is about to stop or may have the word "Brake-on" or any similar word desired by the operator or owner of the car to be used, to indicate that he is applying his brake to stop the vehicle or to slow it down.

A strap 24 of leather or other suitable strong material extends around the shaft 20 and is fixed intermediate its ends to said shaft by a screw or otherwise as shown clearly in Figure 2, and has its opposed ends extended downwardly into the casing 12 and secured one to the spring 11 and the other to a similar spring 25; the lower ends of said springs being engaged with a cross-rod 26 mounted in the lower end of the casing 12.

The head 22 of the semaphore arm 23 has an inwardly and laterally extended pin or stud 27 which projects through an arcuate slot 28 in the adjacent side wall of the casing 12 (see Fig. 3). This arcuate slot 28 is so positioned relatively to the stud 27 as to limit the upward and downward swinging movement of the semaphore 23, said stud engaging the upper end of said slot when the arm 23 is in vertical lowered position as shown in Fig. 3 and engaging the lower end thereof, when said arm is swung upwardly in a plane at right angles of the casing.

A caplike closure 29 fits over the upper end of the casing 12 and is detachably secured thereto to afford access to the interior 40 of the casing when desired.

In the use of this signal the casing 12 carrying the arm 23 is mounted at any suitable point on the car as above stated preferably at the rear thereof and the casting or block 1 is secured to the bottom of the car so as to position the bar 2 in the path of a laterally extending finger or lug 30 carried by the brake rod 31 as is shown clearly in Figs. 1 and 2, so that when the brake is applied the forward movement of the rod will cause said finger 30 to engage bar 2 and swing it on its pivotal connection with the casting 1 thereby exerting a pull on cable 10 which operates through the springs and slot 24 to rotate the shaft 20 and swing the arm 23 into its extreme upward position at right angles to the casing 1 thereby displaying the signal carried thereby and indicating to following vehicles that he is applying his brake to stop or slow down his car. Immediately the brake is released the stud or finger 30 will be moved away from the bar 2 and permits said bar under the action of the spring 25 and the gravity of arm 23 to move into vertical position thus permit-

ting said arm to drop into inoperative position with the signal withdrawn. From the above it will be seen that this signal is automatically operated on the application of the brake and similarly released when the 70 brake is released so that after it is once applied it requires no further attention to ensure its operation.

The signal operating finger 30 which is carried by the brake rod obviously may be attached to said rod in any desired manner and as here shown is carried by a split clamping collar 32, detachably mounted on the brake rod. The collar carrying the finger of course forms a part of the signal equipment and is applied with the apparatus constituting the invention.

From the above description it will be obvious that this improved signalling apparatus may be readily applied to any car already in use by inexperienced workmen, all that is necessary being to properly position the block 1 relatively to the brake rod under the car and to clamp the actuating finger 30 on said rod at the proper position to cause it to come into action at the proper time to raise arm 23 when the brake is applied.

The preferred embodiment of the invention is disclosed in the drawings and set forth in the specifications, but it will be understood that any modifications within the scope of the claims may be made in the construction without departing from the principle of the invention or sacrificing any of its advantages.

What I claim is:—

1. An apparatus for the purpose set forth comprising an attaching block adapted to be secured to a vehicle body, an oscillatory bar pivotally connected to one end and depending from said block, a stirrup straddling and pivotally connected to the lower end of the rod, a threaded bolt carried by and projecting from said stirrup and at an angle with respect to said rod, an adjusting member mounted on the bolt, means arranged within said member and adjustably mounted on the threaded portion of the bolt for adjusting said member relatively to the bolt, a movable signal adapted to be supported from the vehicle body, and a flexible element attached to said member and signal for operating the latter when the bar is shifted.

2. An apparatus for the purpose set forth comprising a casing, supporting means therefor, a rock shaft mounted in and having one end projecting from one wall of said casing, a signal arm secured on the projecting end of said shaft and exterior of said casing and adapted to be elevated and lowered when said shaft is rocked in opposite directions, a pair of coiled springs arranged within and having their lower

ends secured to the bottom of said casing, a flexible strip secured at its ends to the upper ends of said springs and extended over and secured to said shaft and actuated on the application of the braking element of a vehicle to shift said shaft to elevate said signal arm, and a connection between the

upper end of one of said springs and the brake element actuating means of a vehicle, whereby the arm is raised on the application 10 of the braking element of the vehicle.

In testimony whereof, I affix my signature hereto.

FREDERICK J. RYAN.
